FOLDING PLAY-YARD

Robert W. Beaman and James W. Hendricks, Gardner, Mass., assignors to Gem Crib and Cradle Company, Gardner, Mass., a corporation of Massachusetts

Application April 14, 1955, Serial No. 501,308

17 Claims. (Cl. 5—99)

This invention relates to a new and improved folding play-yard in which the floor is foldable against a wall thereof and the wall on which the floor is folded is manipulated in order to extend the floor to useful operative condition; the provision of a folding play-yard including a folding multipart floor having an edge pivotally secured to a wall of the play-yard, the remainder of the floor being free of the play-yard construction, and said wall being movable to fold and extend the floor; and the provision of a folding play-yard as above described wherein the wall is pivotally mounted on a horizontal axis between a pair of corner posts and upon being rotated in a certain direction folds the floor so as to allow the remainder of the play-yard construction to be folded into a small space and upon being reversely rotated causes the floor to be extended into useful condition.

Still further objects of the invention include the provision of a folding play-yard as above described including a depending member located approximately on the dividing line between two parts of the folding floor and causing the folding floor to be properly extended and folded by sliding camming contact with a fixed member of the folding play-yard construction, said fixed member including a rail connecting the corner posts above described and forming a rigid support for the rotatable wall, said folding floor being supported upon said rotatable wall in folded condition of the play-yard and extending in part thereover at the top thereof.

Other objects and advantages of the invention will appear hereinafter.

Reference is to be had to the accompanying drawings, in which

Fig. 1 is a view in front elevation showing the play-yard in extended condition;

Figs. 2 and 3 are enlarged sections on the respective lines in Fig. 1;

Fig. 4 is a section on line 4—4 of Fig. 3;

Figs. 5 and 6 are enlarged sections on the respective lines in Fig. 1;

Fig. 7 is a section on line 7—7 of Fig. 1;

Figs. 8 to 12 inclusive are diagrammatic views illustrating the operation of the folding construction;

Fig. 13 is a plan view showing the play-yard folded and showing a modification; and

Fig. 14 is a view looking in the direction of arrow 14, Fig. 12.

In illustrating the present invention, the same has been shown as applied to a play-yard which has many parts that are conventional in the play-yard art and such parts have not been exhaustively illustrated but comprise in general a rigid rear wall generally indicated by the reference numeral 10 and comprising the usual upright stiles, a top rail and a bottom rail connecting the same rigidly and a pair of end posts indicated by the reference numeral 12.

The above-described rigid rear wall is hingedly con-

2

nected to a pair of more or less conventional in-swinging side walls 14 hingedly connected as at 16 so that the same may be folded in parallelism with the rear wall 10 and with the front wall to be described substantially as shown in Fig. 13 and as well known in the art.

The in-swinging walls 14 being hingedly connected to the corner posts 12 at corresponding ends are also hingedly connected to front corner posts 18 and 20 by the customary hinges, and the corner posts 18 and 20 are rigidly connected together by a lower rail 22 forming a U-shaped frame closed adjacent the bottom but preferably having legs extending therebelow as indicated at 24, said legs being merely extensions of the corner posts as is customary.

15 The corner posts 18 and 20 are provided with means forming pivot members or pins indicated at 26 and 28. These pivot-pins are aligned and pivotally support rotatably thereon the front wall of the playpen which is generally indicated by the reference numeral 30 and comprises the usual lower rail as at 32, upper rail 34 and the connecting stiles as shown. This front wall is included within the U-shaped frame comprising corner posts 18 and 20 and lower rail 22.

At either end of the front wall 30, it is provided with 25 a relatively larger stile or the like 36 in each of which is provided an opening or passage to receive the respective pivot-pins 26 and 28 as clearly shown in Fig. 1, and the front wall 30 is rotatably mounted by these pins.

Preferably there is provided a crank member 38 fixed 30 to the pin 28 and pin 28 is keyed to the member 36 in which it is located. The crank 38 may therefore be used to rotate the front wall 30 upon its pins. A sliding pin 40 may be used as a handle for crank 38 and this pin 40 may be slid inwardly to the left in Fig. 1 to pass 35 through a passage 42 in the corner post 20 and into a notch 44 in the member 36 to latch the rotatable wall 30 in upright position as shown in Fig. 1.

When it is desired to rotate the front wall 30, pin 40 is withdrawn to the right as clearly shown in Fig. 2 and 40 thus is capable of use as a handle for the crank in out-board relation thereto. However, the pin is thrust inwardly as described to lock the wall 30 and is in out-of-the-way position. The pin 40 is provided with a head 46 which slides in the passage 42 as well as the part 44 but fails to be withdrawn through a corresponding hole in the crank 38 so that as shown in dotted lines in Fig. 2, the member 40 while being used as a handle for the crank is not detachable from the play-yard.

At the opposite end of the wall 30, a longitudinally movable pin 48 may be utilized to lock this end of the rotatable wall of the crank construction at the right-hand side of the play-yard as shown in Fig. 1 may be duplicated here.

The lower rail 32 of the front wall 30 is provided with 55 a series of hinges or the like 50, by which means the floor part 52 is hingedly secured thereto. Floor part 52 may be placed in horizontal position for use of the play-yard when extended as shown in Fig. 7, or it may be pivoted upwardly to rest against the front wall 30 as indicated in Fig. 12 and it will be seen that the floor part 52 has a width equal to the height of the wall 30 or it may be slightly greater.

The floor part 52 terminates in a supporting hinge construction indicated at 54 and this member is adapted to 60 extend across the play-yard and to support the same solidly at each end as upon the usual side rails or supports 56. The edges of the floor parts also rest upon usual supports as will be apparent to those skilled in the art. The hinged element 54 may be as wide or as narrow as desired but it is preferred that it be wide enough to extend across the top of the wall 30 as shown in Fig. 12.

so as to adequately provide for the presence of the play-yard pad 58 which is adapted to be secured in position and folded with the floor.

The hinge part 54 has secured, at its opposite edge, ordinary hinges for floor part 60 which completes the floor and extends all the way to the rear wall 10 and may have its edge supported upon conventional brackets or rests 62 secured to the lower rail of rear wall 10.

A member generally indicated at 64 is provided upon the hinge member 54 and this member may be provided with a caster 66 if desired, but this caster is not necessary to the support of the floor nor to the action of the crib and a plain straight piece of material which is indicated at 68 in Fig. 13 may be used instead as will be made clear hereinafter. By use of the caster, additional support on the floor may be obtained but this is not necessary, as the edges of the floor are all supported and the hinge part 54 is a stiffener.

Assuming that the parts are in the position of Figs. 1 and 7 with the in-swinging side walls and the rear wall 10 extended, and the floor is completely horizontal and supported upon rails 56, the operator in order to fold the playpen unlatches pins 40 and 48 and starts to rotate the rotatable front wall 30 in a clockwise direction as indicated in Fig. 8 in dotted lines. Continuation of this action causes floor part 52 to be withdrawn partially past the confines of the play-yard, and this floor part is then raised, drawing with it hinge part 54 and the other floor part 60 until the member 68 or 64 contacts the fixed rail 22 which connects corner posts 18 and 20.

The member 68 or 64 cannot proceed any further to the left in Fig. 8 and thereby the same is caused to rise vertically as indicated in Fig. 9. Continued clockwise motion of the rotatable wall 30 thereupon causes the floor part 52 to be parallel and in contact with the rotatable wall 30 as clearly shown in Fig. 9. Then the member 68 or the end of the caster rides up over the fixed rail 22, leaving the floor part 60 to depend as shown in Fig. 10; and continued rotation of the wall 30 in a clockwise direction then causes the floor part 60 to come into contact in parallel relation with the opposite side of the rotatable wall 30. When the rotatable wall 30 is again upright with floor part 52 in contact therewith at the inside of the play-yard, and floor part 60 in contact therewith at the exterior side of the play-yard, it will be seen that the hinge part 54 is uppermost and on top of the rotatable wall 30 as clearly shown in Fig. 12. In this position, the rotatable wall may again be latched and the in-folding side walls brought into finally folded condition as shown in Fig. 13.

In order to extend the play-yard, the rear wall 10 is moved outwardly away from the folded parts and the swinging side walls 14 are extended and latched as usual. Then the rotatable wall 30 is once more rotated in a clockwise direction, see particularly Fig. 11, and continued motion in this direction will cause the floor part 60 to become overbalanced in the direction of the arrow A in Fig. 11.

This action of course causes the floor part 60 to come down onto the side rail supports 56 and carries floor part 52 away from wall 30 to the position shown in Fig. 8, whereupon the rotatable wall 30 is moved in the reverse direction as shown by the dotted arrow B in Fig. 8, thus moving floor part 52 in the direction of dotted arrow C in Fig. 8 back toward horizontally extended condition for use, resting upon the side rails 56 as shown in Fig. 7.

It will be seen that this invention provides a folding play-yard which is simple in construction and operation and is inexpensive to manufacture due to the fact that it requires very little hardware, and the construction is strong and rugged and is quickly and easily operated from one position to the other in a matter of seconds without the necessity of external pedals, tools, etc.

Having thus described our invention and the advantages thereof, we do not wish to be limited to the details here-

in disclosed, otherwise than as set forth in the claims, but what we claim is:

1. A folding play-yard comprising a rear wall, folding side walls, and a front wall, a folding floor hinged at one edge to the front wall, means supporting the front wall for motion relative to the side walls for folding the folding floor to be supported in part over the front wall and parallel thereto.

2. A folding play-yard comprising a rear wall, folding side walls, and a front wall, a folding floor hinged at one edge to the front wall, means supporting the front wall for motion relative to the side walls for folding the folding floor to be supported in part over the front wall and parallel thereto, and to extend the floor by dropping the folded floor part from the front wall and pushing the entire floor inwardly by means of the front wall.

3. A folding play-yard comprising a rear wall, folding side walls, and a front wall, a folding floor hinged at one edge to the front wall, means supporting the front wall for motion relative to the side walls for folding the folding floor to be supported in part over the front wall and parallel thereto, and to extend the floor by dropping the folded floor part from the front wall and pushing the entire floor inwardly by means of the front wall, said front wall being pivoted with relation to the play-yard structure, and the floor parts being hinged on an axis parallel to the pivot axis of the front wall.

4. A folding play-yard comprising a rear wall, folding side walls, and a front wall, a folding floor hinged at one edge to the front wall, means supporting the front wall for motion relative to the side walls for folding the folding floor to be supported in part over the front wall and parallel thereto, and to extend the floor by dropping the folded floor part from the front wall and pushing the entire floor inwardly by means of the front wall, said front wall being pivoted with relation to the play-yard structure, and the floor parts being hinged on an axis parallel to the pivot axis of the front wall, said floor including a part adjacent to the front wall having a width at least equal to the height of the front wall.

5. A folding play-yard comprising a front frame, a wall pivoted therein, side walls and a rear wall, a folding floor having a part hinged at one edge to an edge of the pivoted wall and folded thereon by rotation thereof.

6. A folding play-yard comprising a front frame, a wall pivoted therein, side walls and a rear wall, a folding floor having a part hinged at one edge to an edge of the pivoted wall and folded thereon by rotation thereof, said floor including a part having a free edge remote from its hinged edge, said free-edged part being foldable onto the pivoted wall to depend therefrom.

7. A folding play-yard comprising a front frame, a wall pivoted therein, side walls and a rear wall, a folding floor having a part hinged at one edge to an edge of the pivoted wall and folded thereon by rotation thereof, said floor including a part having a free edge remote from its hinged edge, said free-edged part being foldable onto the pivoted wall to depend therefrom in supported relation thereto at the outside aspect thereof, with the hinged floor part at the inside aspect of the pivoted wall.

8. A folding play-yard comprising a front frame, a wall pivoted therein, side walls and a rear wall, a folding floor having a part hinged at one edge to an edge of the pivoted wall and folded thereon by rotation thereof, said floor including a part having a free edge remote from its hinged edge, said free-edged part being foldable onto the pivoted wall to depend therefrom in supported relation thereto at the outside aspect thereof, with the hinged floor part at the inside aspect of the pivot wall, the latter being pivoted on a horizontal axis, and including means to latch the pivoted wall in upright condition.

9. A folding play-yard comprising a front frame, a wall pivoted therein, side walls and a rear wall, a folding floor having a part hinged at one edge to an edge of the pivoted wall and folded thereon by rotation thereof, said floor in-

cluding a part having a free edge remote from its hinged edge, said free-edged part being foldable onto the pivoted wall to depend therefrom in supported relation thereto at the outside aspect thereof, with the hinged floor part at the inside aspect of the pivoted wall.

cluding a part having a free edge remote from its hinged edge, said free-edged part being foldable onto the pivoted wall to depend therefrom in supported relation thereto at the outside aspect thereof, with the hinged floor part at the inside aspect of the pivoted wall, the latter being pivoted on a horizontal axis, and including means to latch the pivoted wall in upright condition, the pivoted wall having the same edge uppermost in both folded and extended condition of the play-yard.

10. A folding structure comprising a U-shaped frame, a wall therein and pivoted by and between the arms of the U, a folding floor having a part hinged at one edge to an edge of the pivoted wall and another floor part of less width hinged to the first-named folding floor part, the latter being of a width at least equal to the height of the pivoted wall.

11. A folding structure comprising a U-shaped frame, a wall therein and pivoted by and between the arms of the U, a folding floor having a part hinged at one edge to an edge of the pivoted wall and another floor part of less width hinged to the first-named folding floor part, the latter being of a width at least equal to the height of the pivoted wall and the floor part of less width being supportable on the wall at the opposite side thereof, the wall and both floor parts being parallel and in juxtaposition in folded condition with the wall in the center.

12. A folding play-yard comprising a rear wall, folding side walls, and a front wall, a folding floor hinged at one edge to the front wall, means supporting the front wall for motion relative to the side walls for folding the folding floor to be supported in part over the front wall and parallel thereto, latch means for use as a handle to move the wall.

13. A folding play-yard comprising a front frame, a wall pivoted therein, side walls and a rear wall, a folding floor having a part hinged at one edge to an edge of the pivoted wall and folded thereon by rotation thereof, means to pivot the wall and a latch to hold the wall upright with the floor folded thereon or selectively extended.

14. A folding play-yard comprising a front frame, a wall pivoted therein, side walls and a rear wall, a folding floor having a part hinged at one edge to an edge of the pivoted wall and folded thereon by rotation thereof, means to pivot the wall and a latch to hold the wall up-

right with the floor folded thereon or selectively extended, said wall pivoting means including the latch and the latter comprising a handle shiftable to connect the pivoted wall with the side walls or selectively to act as a wall turning handle.

15. A folding structure comprising front and rear walls, connecting folding side walls, and an articulated floor, the front wall comprising a U-shaped frame and a wall member pivoted therein on a horizontal axis between the arms of the U, the floor having a connection to the pivoted wall member to be folded over thereon as the wall member is rotated and to be unfolded as the wall member is oppositely rotated, a depending member on the floor, said member contacting the closed end of the U and camming the floor up as the wall member is rotated to fold the floor.

16. A folding structure comprising front and rear walls, connecting folding side walls, and an articulated floor, the front wall comprising a U-shaped frame and a wall member pivoted therein on a horizontal axis between the arms of the U, the floor having a connection to the pivoted wall member to be folded over thereon as the wall member is rotated and to be unfolded as the wall member is oppositely rotated, a narrow hinge strip between the floor parts bridging the top edge of the pivoted wall when the floor is folded.

17. A folding structure comprising front and rear walls, connecting folding side walls, and an articulated floor, the front wall comprising a U-shaped frame and a wall member pivoted therein on a horizontal axis between the arms of the U, the floor having a connection to the pivoted wall member to be folded over thereon as the wall member is rotated and to be unfolded as the wall member is oppositely rotated, a narrow hinge strip between the floor parts bridging the top edge of the pivoted wall when the floor is folded, and a depending camming member on the hinge strip to engage the closed end of the U and raise the floor upon folding the same.
